DESIGN FOR A GOBLET

Norman Moll, Toledo, Ohio, assignor to Libbey
Glass Company, Toledo, Ohio, a corporation of Ohio

Application April 22, 1938, Serial No. 76,707

Term of patent 7 years

To all whom it may concern:

Be it known that I, Norman Moll, a citizen of the United States, residing at Toledo, in the county of Lucas and State of Ohio, have invented a new, original, and ornamental Design for a Goblet, of which the following is a specification, reference being had to the accompanying drawing, forming a part thereof.

In the drawing:

Fig. 1 is a side elevational view of a goblet showing my new design.

Fig. 2 is a top plan view thereof.

I claim:

The ornamental design for a goblet, substantially as shown.

NORMAN MOLL.
